[57] CLAIM

The ornamental design for a fountain pen, substantially as shown and described.

DESCRIPTION

FIG. 1 is a top plan view of a fountain pen showing our new design;
FIG. 2 is a bottom plan view thereof;
FIG. 3 is a front elevational view thereof;
FIG. 4 is a right end elevational view; and
FIG. 5 is a left end elevational view.
The characteristic feature of our design resides in the combination of the chamfered ring adjacent the nib and the ring adjacent the barrel.

FIG. 1

FIG. 2

FIG. 3

FIG. 4

FIG. 5
